UNITED STATES PATENT OFFICE

1,938,131

VENTILATING FLUE CAP

William August Briel, Evansville, Ind.

Application August 11, 1931. Serial No. 556,455

5 Claims. (Cl. 126—316)

This invention relates to that general class of devices used as a flue cap or stopper to close the opening into the chimney or flue which, in cold weather, accommodates the smoke or 5 stove pipe from a stove or heater.

The object of my invention is to provide an improved flue cap, which may be ornamented to enhance its appearance if desired, that will provide for ventilation when the cap is used 10 in those seasons when the stove or heater is disconnected, the purpose being to afford means whereby a draft may enter the chimney or flue, thus taking off the hot air from the room and effecting lowering the temperature so that the 15 room will be cooler throughout the day and night.

Another object is to provide an improved flue cap which, aside from its retaining means, will be wholly located inside of the room.

20 In carrying out my invention, I provide a flue cap of novel construction adapted to be wholly located inside of the room and having screen 25 ventilating openings in its top, and also provided with adjustable inherently springy holders 30 or bails which can be inserted in the flue for the purpose of holding the cap in position to permit the draft or ventilating openings to function while, at the same time, effectually closing the flue opening so far as the appearance 35 is concerned.

Unlike earlier flue caps or stoppers, my improved cap, while covering the flue so that it presents no unsightly appearance, leaves the flue open for the admission of the heated air diving 40 down from the upper part of the room and thus effectually permits the flue or chimney to set up a natural draft which carries off the air from the room, rendering it cooler and cleaner without possibility of soot being blown from the 45 chimney into the room, and without soot being collected by the cap.

In the accompanying drawing:

Figure 1 is a vertical section showing the cap in use;

45 Fig. 2 is a horizontal section through the cap when in use; and

Fig. 3 is a detail perspective view of the cap.

The brickwork of the chimney flue appears 50 at 1 and the interior of the flue is shown at 2; as usual, the chimney has an opening 3 for the reception of the stove pipe or smoke flue from the stove or heater which is used in the room in cold weather. The ceiling of the room appears at 5.

It is customary to provide a flue cap or stop to close the opening 3 in those seasons of the year when the stove or heater is not used, during which periods the stove or heater may be removed from the room.

My improved flue cap or stopper is shown at 4, being provided with triangular shaped sides 5, a rectangular shaped top 6, and an inclined front or face 7. The front 7 may be of the square shape shown and provided with any suitable design, picture or ornamentation to enhance its appearance. The width of the cap between the sides 5 is greater than the diameter of the flue hole 3 and the vertical edges 8 of said sides lie flat against the wall or chimney 1, 60 as the case may be. The top 6 is provided with one or more openings 9, covered by a suitable screen or screens 10. As shown, there are a plurality of independent openings 9 but it will be understood that a single opening may be 65 substituted and covered with a single screen. The purpose of the screen or screens is to serve as a barrier between the air in the room and in the chimney to prevent down drafts in the chimney from bringing soot, dust, etc. into the 70 room and also to prevent the entry of bats into the room.

The natural draft created by the flue 2 draws the warmer air from the upper part of the room down through the opening or openings 9, the opening 3 and into the chimney, thus tending to keep the room cooler in hot weather than is possible with flue caps or stoppers which snugly fit against the stove pipe opening 3 and prevent draft of this character from taking place.

One or more inherently flexible bow-shaped bails or holders 11, which are hinged at 12 to the inside of the front 7, protrude into the hole 3, or the thimble or pipe section or bushing therein and by frictionally contacting therewith, 85 retain the cap in position.

By hinging the bail or bails 11 at 12, they naturally adjust themselves when the cap is placed in position so that the cap is better held in position. I have also found that providing two of these resilient bails 11, located one above the other, a superior holding action of the cap is obtained.

The arrows indicate the down draft from the upper part of the room whereby the heated air is drawn off by the flue 2 through the openings 9.

What I claim is:

1. In combination with a flue opening, a box-like flue cap having vertically extending sides provided with straight rear edges adapted to lie 110

against that wall of the flue which faces the inside of the room and provided with a front connecting said sides and with a top located above the flue opening so as to be inaccessible to soot, said top having a ventilating opening, and a bow-shaped bail whose ends are hinged to the rear face of the front and which is adapted to be inserted in the flue opening.

2. In combination with a flue opening, a box-like flue cap having vertically extending sides provided with straight rear edges adapted to lie against that wall of the flue which faces the inside of the room and provided with a front connecting said sides and with a top which has a ventilating opening, said top being disposed in general horizontal position above the flue opening so as to be inaccessible to soot, and said front being downwardly inclined from the top, and a bow-shaped bail whose ends are hinged to the rear face of the front and which is adapted to enter the flue opening for the purpose of retaining the cap in position.

3. In combination with a flue opening, the herein described box-like ventilating cap for the flue opening comprising triangular side walls which are widest at their tops, and have vertical rear edges adapted to lie against opposite sides

of the flue opening which faces the inside of the room, a top which connects said triangular side walls above the flue opening and is provided with an opening for ventilating purposes which is inaccessible to soot, a downwardly inclined front connecting said side walls, and a bow-shaped bail whose ends are hinged to the rear face of the front and adapted to enter the flue opening for the purpose of retaining the cap in position, said cap constituting a diving flue by which the warmer upper air may be drawn down through the top and into the flue opening while said cap serves as a cover for the flue opening.

4. In combination with a flue opening, a flue cap covering the flue opening and having an upper part located above the flue opening, said upper part being provided with a ventilating opening disposed above the flue opening, and means for holding the cap in position.

5. In combination with a flue opening, a flue cap covering the flue opening and having an upper horizontal part located above the flue opening and provided with a ventilating opening disposed above the flue opening, and means for holding the cap in position.

WILLIAM AUGUST BRIEL.
